UNITED STATES PATENT OFFICE.

ARTHUR V. ADAMSON, OF HEMPSTEAD, NEW YORK, ASSIGNOR TO COMBUSTION ENGINEERING CORPORATION, A CORPORATION OF NEW YORK.

HANDLING AND FEEDING OF PULVERIZED COAL.

Application filed November 19, 1924. Serial No. 750,781.

To all whom it may concern:

Be it known that I, ARTHUR V. ADAMSON, a citizen of the United States, residing at Hempstead, in the county of Nassau and State of New York, have invented certain new and useful Improvements in the Handling and Feeding of Pulverized Coal, of which the following is a specification.

This invention relates to systems for the handling of pulverized fuel and is especially useful in connection with such systems as are associated with a furnace or combustion chamber for the burning of such fuel.

More specifically the invention is useful in systems having a closed circulation of carrying air.

One of the primary objects of my invention is to overcome difficulties arising from condensate which, in the absence of provision to the contrary, such as I propose, sometimes causes clogging and other difficulties.

How the foregoing, together with such other objects as may hereinafter appear, or are incident to my invention, are obtained is illustrated in the accompanying drawings wherein:

Fig. 1 is a side elevation of a system in connection with which my invention is useful, such figure showing one arrangement of my improvement;

And Fig. 2 is a fragmentary view showing another form of my invention and one which is particularly adapted to systems which are associated directly with a furnace to be supplied with pulverized coal.

Referring now to Fig. 1, reference character A denotes the combustion chamber in which the fuel is to be burned, such fuel being prepared by the mill B supplied from a suitable source with crushed coal. From the mill, the pulverized coal is led by the pipe 7 to the cyclone separator 8 where the coal is separated from the air, the air being returned to the mill by way of the return pipe 9. Circulation thru this system is brought about by the fan 10. The coal collected in the cyclone separator is discharged into the bin 11 from which it is fed to the burners 12 of the combustion chamber by the feeder mechanism 13.

The system described has closed circulation of the air but there is some leakage into such systems to which end a vent is

sometimes employed at the point marked 14 65 which vent, in this case, is normally closed. Where the system is associated with the furnace to be fed, I prefer to vent the excess air in the system directly to the feeder for the reason that there is some coal carried in 60 suspension in such excess air. To this end the return pipe has an enlargement 15 from which the excess air is drawn off thru the conduit 16 by the fan 17 and led to the feeder 13. 65

In the arrangement of Fig. 1, I take care of the condensate by locating a condensate collector 18 immediately below the point where the return pipe 9 discharges into the mill casing. The condensate in the return 70 line drips down into this collector by gravity. In many instances the condensate carries with it moist coal particles or, to state the matter in another way, some of the coal particles become moisture laden and gravitate into the collector. 75

Referring now to the arrangement of Fig. 2, it will be seen I have arranged the condensate collector 18 in advance of the fan 17 i. e. between such fan and the return 80 pipe 9. The conduit 16 bends downwardly after leaving the member 15 and at the bottom of the bend or elbow I provide a connection 19 leading to the condensate collector. 85

Most of the difficulty encountered in connection with condensate has its seat in the return line and by drawing off the excess air in the manner described sufficient moisture is withdrawn to prevent difficulty in 90 the system. By collecting the condensate from the vapors drawn off in the conduit 16, clogging in the feeder and in the line to the feeder is overcome. From time to time the 95 collector is cleaned.

I claim:

1. The combination in a fuel supply system, with a closed circulation of carrying air, a mill, a separator, a pipe from mill to the separator, a return pipe, a feeder, a conduit for conveying excess air in the system to the feeder, and a condensate collector for such conduit. 100

2. The combination in a fuel supply system with a closed circulation of carrying air, a mill, a separator, a pipe from mill to the separator, a return pipe, a feeder, a furnace to be fed, a conduit for removal of ex- 105

cess air in the system to the feeder, and a gravity condensate collector in said conduit.

3. The combination in a fuel supply system, with a closed circulation of carrying air, a mill, a separator, a pipe from mill to the separator, a return pipe, a feeder, a conduit for conveying excess air in the system

to the feeder, a fan in said conduit, and a condensate collector on the intake side of the fan.

In testimony whereof, I have hereunto signed my name.

ARTHUR V. ADAMSON.
